CLAIM

The ornamental design for a shoe heel as shown and described.

DESCRIPTION

FIG. 1 is a rear perspective view of the shoe heel in the form of a letter "C";

FIG. 2 is a right side view of the shoe heel of FIG. 1;

FIG. 3 is a left side view of the shoe heel of FIG. 1;

FIG. 4 is a front view of the shoe heel of FIG. 1;

FIG. 5 is a rear view of the shoe heel of FIG. 1;

FIG. 6 is a top view of the shoe heel of FIG. 1; and,

FIG. 7 is a bottom view of the shoe heel of FIG. 1.

The broken lines shown in the drawings represent portions of the shoe heel that form no part of the claimed design.
